FIG. 2

FIG. 3

FIG. 4

FIG. 5

By *Paul E. Eaton*
ATTORNEY.

J. A. McKAUGHAN,
INVENTOR.

UNITED STATES PATENT OFFICE

JESSE A. MCKAUGHAN, OF TROUTMANS, NORTH CAROLINA.

TOBACCO STICK

Application filed June 21, 1930. Serial No. 462,860.

This invention relates to an improved tobacco stick on which to hang tobacco for curing as it is now the practice among a large percentage of tobacco growers to strip 5 the leaves off of the tobacco plant and bring them outside the field and secure a handful of tobacco alternately on each side of the stick by securing a string at one end of the stick underneath a splinter of the conventional tobacco stick now used and wrapping 10 a string around a bunch of tobacco on one side of the stick and then crossing the stick to the other side and wrapping a string around a bunch of tobacco on the other side 15 of the stick and continuing until the stick has been filled with a bunch of tobacco and then securing the end of the string in position at the end of the stick. This has been done heretofore largely in using the ordinary wooden stick and fastening the 20 twine used to bind the tobacco onto the stick underneath splinters and other obstructions on the stick.

It is an object of my invention to provide 25 a metallic stick with means for securing the twine at each end of the stick and in providing a stick which is reinforced and strong. I eliminate any fire hazard due to the possibility of a stick breaking and allowing 30 the tobacco to fall down into the bottom of the curing barn for sometimes it falls on heated flues and becomes ignited and the barn is destroyed.

Another object of my invention is to provide 35 a tobacco stick made of metal and which is reinforced to prevent its bending and to give the proper strength thereto and at the same time to be practically indestructible and capable of long life and usefulness.

40 Some of the objects of my invention having been stated other objects will appear as the description proceeds, when taken in connection with the accompanying drawings, in which—

45 Figure 1 is a side elevation of my improved stick;

Figure 2 is a bottom plan view of my stick before the same is folded into proper shape;

50 Figure 3 is a bottom plan view of the stick after the edges have been turned inwardly

to form the reinforcing structure and before the stick is given its final bend to make a stick which is V-shaped in cross-section or rather an inverted V-shape;

Figure 4 is a view taken along the line 55 4—4 in Figure 3;

Figure 5 is a perspective view of the end of the stick after the same has been completed and folded to proper position;

Figure 6 is a modified form of the fastening means which may be stamped out of the end of the stick.

Referring more particularly to the drawings the numeral 10 indicates the tobacco stick as a whole and this is formed by turning the portions 11 and 12 inwardly to reinforce the stick and then after turning the portions 11 and 12 inwardly to bend the stick along the line 13 which becomes the top portion of the stick as shown in Figure 5. During the operation of manufacturing the stick and preferably at the time the pieces are cut and before folding, the V-shaped slots 15 and 16 will be cut in opposite side portions in opposite ends of the stick, it being evident that the twine for securing the tobacco on the stick can be secured in the notch 15 and at the end of the wrapping operation the other end of the twine can be secured in the notch 16 merely by tying a knot in the end of the 50 twine.

If desired I can provide the tongue 17 instead of the notches 15 and 16 and the twine can be wrapped around this tongue.

After the stick has been folded along the edges as shown in Figure 3 it is then bent in the middle along line 13 and provides an inverted V-shaped member which is inverted V-shaped in cross-section as shown in Figure 5 and the shape of the stick and the reinforcement given to it by the bending of the same and also by the over-lapping edges 11 and 12 provides a strong stick which will not bend unduly and which will support the required amount of weight which it will be accustomed to bear. The strength of the stick can be regulated by the thickness of the metal out of which it is made which is preferably sheet metal and if made out of galvanized sheet metal will be practically inde- 100

structible on account of rust not taking effect on the same. Also the width of the overlapping edges 11 and 12 can be increased to give further strength to the stick if desired.

5 In the drawings and specification I have set forth a preferred embodiment of my invention, and although specific terms are employed, they are used in a generic and descriptive sense only, and not for purposes of limitation, the scope of the invention being 10 set forth in the appended claims.

I claim:

1. A tobacco stick formed of sheet metal and being over-lapped at its edges and bent 15 into an inverted V-shape in cross-section and having a notch in each end thereof.

2. A tobacco stick composed of sheet metal, said tobacco stick comprising reinforced edge portions, and being bent into a shape 20 which is an inverted V-shape in cross-section, notches in each end of the tobacco stick for securing a twine therein.

25 3. A tobacco stick made of sheet metal and comprising over-lapped edge portions, said tobacco stick being bent with one side portion at approximately a right angle to the other side portion and forming an inverted V-shaped member in cross-section with notches in each end of the stick for securing 30 twine therein.

35 4. A tobacco stick made of sheet metal and being doubled along its edge portions to provide reinforcement and being bent along its central portion to provide a member which is an inverted V-shape in cross-section and means on each end of the member for securing a twine therein.

In testimony whereof I affix my signature.

JESSE A. McKAUGHAN.
